United States Patent Office

Des. 203,222
Patented Dec. 14, 1965

203,222

VENDING MACHINE

William C. Christine, Catasauqua, and Joseph E. Pierce,
Allentown, Pa., assignors to Allen Electronics, Inc.,
Bethlehem, Pa., a corporation of Pennsylvania

Filed Oct. 1, 1964, Ser. No. 81,978

Term of patent 14 years

(Cl. D52—3)

FIG. 1

FIG. 2

FIG. 3

FIG. 4

FIG. 5

FIG. 6

FIGURE 1 is a front elevational view of the vending machine showing our new design.

FIGURE 2 is an elevational view taken from one side thereof.

FIGURE 3 is a bottom plan view thereof.

FIGURE 4 is a top plan view thereof.

FIGURE 5 is a rear elevational view.

FIGURE 6 is an elevational view taken from the side opposite that shown in FIGURE 2.

We claim:

The ornamental design for a vending machine, as shown.
